US0D1104593S

(12) **United States Design Patent** (10) **Patent No.:** **US D1,104,593 S**
Vargo (45) **Date of Patent:** **** Dec. 9, 2025**

(54) **PORTABLE COLLAPSIBLE POLYGONAL STOVE ASSEMBLY WITH LOADING AND VENTILATION APERTURES**

(71) Applicant: **Brian J Vargo**, Lewisburg, PA (US)

(72) Inventor: **Brian J Vargo**, Lewisburg, PA (US)

(**) Term: **15 Years**

(21) Appl. No.: **29/953,686**

(22) Filed: **Jul. 23, 2024**

(51) **LOC (15) Cl.** **07-02**

(52) **U.S. Cl.**

USPC **D7/332**

(57) **CLAIM**

The ornamental design for the portable collapsible polygonal stove assembly with loading and ventilation apertures, as shown and described.

DESCRIPTION

FIG. 1 is a front elevational view of my design;
FIG. 2 is a rear elevational view of my design;
FIG. 3 is a top right side view of my design;
FIG. 4 is a top left side view of my design;
FIG. 5 is a top view of my design;
FIG. 6 is a top elevational view of my design;
FIG. 7 is a bottom view of my design;
FIG. 8 is an exploded front elevational view of my design, partially illustrating the collapsible feature; and,
FIG. 9 is an exploded front elevational view of my design, illustrating the collapsible feature.

1 Claim, 6 Drawing Sheets
